CASTING EJECTOR

Helmer V. Kruse, Douglas, Ariz.

Application September 28, 1950, Serial No. 187,238

8 Claims. (Cl. 25—120)

1

The present invention relates to improvements in casting ejectors and more particularly to a device comprised of a first frame and an ejector frame, the frames providing a mold.

An object of the present invention is to provide an improved casting ejector wherein the ejector frame is movable relatively to the first frame whereby the casting may be forced from the confining walls of the first frame.

Another object of the present invention is to provide an improved actuating means whereby the ejector frame may be moved relative to the first frame so that the first and ejector frames remain in axial alignment during the ejecting operation.

Still another object of the present invention is to provide an arrangement wherein coring means may be removably attached to the first frame as desired.

A further object of the present invention is to provide a casting ejector which is simple in construction, economical of manufacture, easily adjusted to provide a mold and readily power actuated in an inverted position for ejecting the casting.

Various other objects and advantages will become apparent from the detailed description to follow. The best form in which I have contemplated applying my invention is clearly illustrated in the accompanying drawings, wherein:

Figure 1 is a vertical longitudinal sectional view of the casting ejector in its upright position providing a mold;

Figure 2 is a vertical transverse sectional view taken substantially along the plane of line 2—2 of Figure 1;

Figure 3 is a side elevational view of the casting ejector shown in its inverted position preparatory to ejecting the casting;

Figure 4 is a horizontal longitudinal sectional view taken substantially on the plane of line 4—4 of Figure 3;

Figure 5 is a view similar to Figure 3 but wherein the power actuating means has been operated to effect ejection of the casting;

Figure 6 is a vertical transverse sectional view taken substantially along the plane of line 6—6 of Figure 5;

Figure 7 is a horizontal longitudinal sectional view taken substantially along the plane of line 7—7 of Figure 3; and

Figure 8 is an end elevational view as seen from the right of Figure 4.

Referring more particularly to the drawings,

2

wherein like numerals designate like parts throughout, the numeral 10 designates generally the casting ejector of the present invention which is comprised of a first frame 12 and an ejector frame 14, the first frame 12 and the ejector frame 14 being relatively movable with respect to each other. The invention also comprises a power actuating means 16 for effecting relative vertical movement between the frames and a core means 18 which may be mounted on the first frame.

The first frame 12 includes a pair of channeled end members 20 and 22 forming end walls 24 and 26, a pair of channeled side members 28 and 30 forming side walls 32 and 34 and joining the end members 20 and 22, and the side members 28 and 30 are substantially reduced in height with relation to the end members 20 and 22 as seen in Figure 2. Thus, the end walls 24 and 26 and side walls 32 and 34 provide the upstanding walls of a mold in which the casting 36 is to be cast.

As seen best in Figures 1 and 7, a plurality of T-shaped supports 38 connect the channeled members 28 and 30 at spaced positions along their lengths. The ends of the T-shaped supports 38 may be secured in any desired fashion to the channeled members 28 and 30 and the bars 40 which form an element of each of the T-shaped supports are in upstanding relation to provide supporting surfaces for the wall 42. A strap 44 also extends between the channeled members 28 and 30 and is removably attached thereto by means of the bolts 46. The strap 44 is adapted to support the coring means 18 which is here shown in the form of a rectangular block 48 which is secured to the strap 44 by means of a plurality of screws 50. Of course, coring means of various forms may be employed and their positioning within the frame will be as desired.

The wall 42 is of rectangular shape and is adapted to slidably engage the walls 24, 26, 32 and 34 with an opening 51 being provided therein for slidably receiving the core 48. The wall 42 which forms the bottom of the mold is attached to the ejector frame 14 by means of a plurality of upstanding posts 52 which are rigidly secured to the underside of the wall 42. The opposite ends of the posts 52 are fixedly secured to a plurality of transversely extending bars 54 which form a part of the ejector frame 14.

The ejector frame 14 is comprised of a pair of substantially U-shaped longitudinally extending side elements 56 and 58 which have their bight

portions 60 and 62 joined by the plurality of bars 54. Bolts 64 are employed for securing the bight portions 60 and 62 of the ejector frame to the extremities of the bars 54. Thus it will be seen that the bottom wall 42 is rigidly supported in spaced relation to the bars 54 and is adapted to move unitarily with the ejector frame 14.

The leg portions 66, 68, 70 and 72 are adapted to be slidable through the outstanding portions 74 and 76 of the channeled element 28 and through the outstanding portions 78 and 80 of the channeled element 30. Each of the leg portions 66, 68, 70 and 72 is formed as a gear rack and each of the gear racks faces a common direction.

The means for effecting relative movement between the first frame 12 and the ejector frame 14 is designated generally as the power actuating means 16. The power actuating means is best shown in Figures 3 and 4 and is comprised of a pair of power cylinders 82 and 84 which are longitudinally disposed. Each of the power cylinders 82 and 84 has one end thereof supported by a bolt 86 which is secured to one of the side elements 28 and 30. The power cylinders 82 and 84 are of hollow construction provided with end closure elements 88 and 90. A fluid supply conduit 92 has branch tubes 94 and 96 leading to the end closures 88 of the cylinders 82 and 84 to supply fluid behind the piston 98 which is slidably disposed within the cylinders. Plungers 100 are secured to the pistons 98 in each of the cylinders 82 and 84 and extend outwardly through the end closures 90. The free end of the plunger rod 100 of each of these cylinders 82 and 84 is supported by a sleeve 108 which is integrally formed with a bracket 108 which is, in turn, secured to one of a pair of longitudinally disposed rack bars 102 and 104. A pin 107 extends through the sleeve 108 to connect the plunger 100 therein and a pair of pins 109 secure the bracket 108 to the individual rack bars 102 and 104.

The rack bars 102 and 104 are longitudinally and slidably mounted on the first frame 12 and have their end portions adapted to slide through openings 110 and 112 in the channeled members 20 and 22. A pair of gears 114 and 116 is disposed on each side of the first frame 12 and within the channeled elements 28 and 30. The gears are mounted on supporting bolts 118 which are secured to the side walls 28 and 30 with spacing sleeves 120 maintaining the gears in spaced relation thereto. The gears 116 are both connected to a shaft 122 which is rotatably disposed in a pair of bearing brackets 124 and 126 which are fixedly secured to the end member 22.

Each of the gears 114 and 116 is positioned for operative engagement with the vertically disposed rack bars 70 and 72 and the longitudinally disposed gear racks 102 and 104.

From the foregoing description taken in conjunction with the drawings, it is believed that the manner in which the casting extractor is operated will be readily apparent to one skilled in the art. When the casting ejector 10 is in its upstanding position as shown in Figure 1, the side walls 32 and 34 and the end walls 24 and 26 cooperate with the bottom wall 42 of the ejector frame 14 to provide a mold. The corning means 18 is supported by the first frame 12. The material to be cast is then poured into the mold and allowed to solidify. Next, the cast-

ing ejector is inverted to the position shown in Figure 3 and fluid under pressure is admitted to the power cylinders through the conduit 92, thereby effecting longitudinal movement of the pistons 98 against the urging of the coil compression springs 99. The longitudinal movement of the pistons 98 will be accompanied by longitudinal movement of the racks 102 and 104. Inasmuch as the gears 114 and 116 are in operative engagement with the racks 102 and 104, they will rotate in similar directions. Rotation of the gears 114 and 116 will raise the first frame 12 with respect to the ejector frame 14 because of the engagement between the gears 114 and 116 and the vertically disposed rack bars 70 and 72 of the ejector frame. Inasmuch as the bottom wall 42 is rigidly secured to the ejector frame 14, the bottom wall will not rise with the first frame 12 and the walls 24, 26, 32 and 34 will rise vertically while slidably contacting the outer periphery of the bottom wall 42 until the first frame 12 reaches the position shown in Figures 5 and 6. The core 48, being attached to the first frame 12, will rise in unison with the first frame and the casting 36 will be forcibly maintained on the supporting surface 37 for the casting ejector.

After the casting 36 has been ejected from the mold, the fluid pressure may be cut off and the casting ejector inverted for again providing a mold. The coil springs 99 will urge the pistons 98 to their normal positions and the first and ejector frames will again be in their original relation as shown in Figure 1.

In view of the foregoing description, it is believed that a device has been provided which will accomplish all of the objects hereinabove set forth. Of course, various mechanical modifications may be made which will fall within the scope of the appended claims.

Having described the invention, what is claimed as new is:

1. A casting ejector comprising a first frame having end and longitudinal members providing walls for a mold, a plurality of transversely extending bars having their ends secured to said side members at points intermediate the open ends of said first frame, core means detachably connected to preselected of said bars, an ejector frame mounted within said first frame, an ejector wall disposed within said first frame and in sliding contact with the members and providing a bottom wall for the mold when in its upright position, said ejector wall being fixedly secured in spaced relation to one end of said ejector frame, said first and ejector frames being reciprocably mounted with respect to each other, and power actuated means for effecting relative movement between said first frame and ejector frame when in a second position inverted to the upright position whereby the casting within the mold may be ejected, said power actuated means including at least one power cylinder having one end attached to said first frame exteriorly of said longitudinal members, horizontally disposed rack means disposed in parallel relation to said power cylinder and mounted for reciprocating movement on said first frame, the plunger of said power cylinder being connected for effecting longitudinal movement of said rack means upon actuation of said power cylinder, gears mounted on opposite ends of said first frame and operatively engageable with said rack means for rotation upon longitudinal movement of said rack means, said ejector frame having in-

tegrally formed therewith vertically disposed rack means operatively engageable with said gears whereby rotation of said gears effects movement of said ejector frame with respect to said first frame.

2. A casting ejector comprising a first frame, an ejector frame mounted within said frame, said first and ejector frames together providing a casting mold, said ejector frame including a pair of substantially U-shaped longitudinal side elements joined in spaced relation by a plurality of cross bars and slidably engaged in openings through the sides of said first frame, the free ends of the legs of said U-shaped elements providing supporting legs for the first and ejector frame when in their inverted ejecting position, said legs being formed as gear racks facing a common direction, gears rotatably supported by said first frame and operatively engageable with said gear racks, and second gear racks for effecting rotation of said gears thereby effecting relative movement between said first and ejector frames.

3. A casting ejector comprising a first frame, an ejector frame mounted within said frame, said first and ejector frames together providing a casting mold, said first frame including a pair of channeled end members forming end walls, a pair of channeled side members forming side walls and joining said end walls, said side members being substantially reduced in height with relation to said end members, said ejector frame including a pair of substantially U-shaped longitudinal side elements joined in spaced relation by a plurality of cross bars, the legs of said side elements being slidably engaged through the side members of said first frame, the free ends of the legs of said U-shaped elements providing supporting legs for the first and ejector frames when in their inverted ejecting position, said legs being formed as gear racks facing a common direction, gears rotatably supported by said first frame and operatively engageable with said gear racks, and second gear racks for effecting rotation of said gears thereby effecting relative movement between said first and ejector frames.

4. A casting ejector comprising a first frame, an ejector frame mounted within said frame, said first and ejector frames together providing a casting mold, said ejector frame including a pair of substantially U-shaped longitudinal side elements joined in spaced relation by a plurality of cross bars, the free ends of the legs of said U-shaped elements providing supporting legs for the first and ejector frame when in their inverted ejecting position, said legs being formed as gear racks facing a common direction, gears rotatably supported by said first frame and operatively engageable with said gear racks, and means for effecting rotation of said gears thereby effecting relative movement between said first and ejector frames, said means including at least one power cylinder having one end attached to said first frame and being horizontally disposed, a horizontally disposed gear rack in juxtaposition to said power cylinder and slidably disposed on said first frame and operatively engageable with said gears, a piston and plunger reciprocably mounted within each of said power cylinders and actuated by fluid pressure, means connecting each of said plungers with the juxtaposed gear rack.

5. A casting ejector comprising a first frame, an ejector frame mounted within said frame, said first and ejector frames together providing a casting mold, said first frame including a pair of channeled end members forming end walls, a

pair of channeled side members forming side walls and joining said end walls, said side members being substantially reduced in height with relation to said end members, said ejector frame including a pair of substantially U-shaped longitudinal side elements joined in spaced relation by a plurality of cross bars, the free ends of the legs of said U-shaped elements providing supporting legs for the first and ejector frames when in their inverted ejecting position, said legs being formed as gear racks facing a common direction, gears rotatably supported by said first frame and operatively engageable with said gear racks, and means for effecting rotation of said gears thereby effecting relative movement between said first and ejector frames, said means including at least one power cylinder having one end attached to said first frame and being horizontally disposed, a horizontally disposed gear rack in juxtaposition to said power cylinder and slidably disposed on said first frame and operatively engageable with said gears, a piston and plunger reciprocably mounted within each of said power cylinders and actuated by fluid pressure, means connecting each of said plungers with the juxtaposed gear rack.

6. A casting ejector comprising a first frame having end and longitudinal members providing walls for a mold, a plurality of transversely extending bars having their ends secured to said side members at points intermediate the open ends of said first frame, core means detachably connected to preselected ones of said bars, an ejector frame mounted within said first frame, an ejector wall disposed within said first frame and in sliding contact with the members and providing a bottom wall for the mold when in its upright position, said ejector wall being fixedly secured in spaced relation to one end of said ejector frame, said first and ejector frames being reciprocably mounted with respect to each other, and power actuated means for effecting relative movement between said first frame and ejector frame when in a second position inverted to the upright position whereby the casting within the mold may be ejected, said power actuated means including at least one power cylinder having one end attached to said first frame exteriorly of said longitudinal members, horizontally disposed rack means disposed in parallel relation to said power cylinder and mounted for reciprocating movement on said first frame, the plunger of said power cylinder being connected for effecting longitudinal movement of said rack means upon actuation of said power cylinder, gears mounted on opposite ends of said first frame and operatively engageable with said rack means for rotation upon longitudinal movement of said rack means, said ejector frame having integrally formed therewith vertically disposed rack means operatively engageable with said gears whereby rotation of said gears effects movement of said extractor frame with respect to said first frame.

7. A casting ejector comprising a first frame, an ejector frame mounted within said first frame, said first and ejector frames together providing a casting mold, said ejector frame including a pair of substantially U-shaped longitudinal side elements joined in spaced relation by a plurality of cross bars and slidably engaged in openings through the sides of said first frame, the free ends of the legs of said U-shaped elements providing supporting legs for the first and ejector frames when in their inverted ejecting position, said legs being formed as gear racks facing a common direction, gears rotatably supported by

said first frame and operatively engageable with said gear racks, a shaft connecting a pair of said gears for simultaneous rotation, and second gear racks for effecting rotation of said gears thereby effecting relative movement between said first and ejector frames.

8. A casting ejector comprising a first frame, an ejector frame slidably mounted within said first frame, said first frame in combination with a moveable bottom carried by said ejector frame forming a mold, said ejector frame having vertical legs with gear racks formed thereon, gears rotatably carried by said first frame in engagement with said gear racks, second gear racks carried by said first frame in engagement with

15 said gears, means for moving said second gear racks longitudinally.
